DRIER

Filed Sept. 28, 1922

UNITED STATES PATENT OFFICE.

GUILFORD L. SPENCER, OF HERRICKS, MAINE.

DRIER.

Application filed September 28, 1922. Serial No. 591,144.

To all whom it may concern:

Be it known that I, GUILFORD L. SPENCER, a citizen of the United States, and a resident of Herricks, in the county of Hancock and State of Maine, have invented a new and Improved Drier, of which the following is a full, clear, and exact description.

This invention relates to a drier, and aims to provide a device of this nature by which 10 an operator shall be enabled rapidly to determine the amount of moisture in laboratory tests of various substances.

A further object of this invention is the provision of an oven which will enable the 15 analyst to make rapid control tests in factory work and in laboratories generally. Although this device may be used for determining the amount of moisture in any substance, the same is particularly adapted for 20 use in connection with tobacco and fibrous materials in which it is essential to carefully control the moisture content of the product in order that it may be kept within certain limits.

25 Such a drier was disclosed in United States Letters Patent No. 1,348,757, issued to me.

The object of the present invention is to provide a drier of a different but practical 30 and efficient structure, having important advantages peculiar to itself, all as will be clearly understood from the following description when taken in connection with the accompanying drawing showing as an example of the present invention, a preferred but merely illustrative embodiment.

In said drawing the view shows such drier in vertical axial section.

The numeral 2 indicates a casing preferably provided with a removable lid such as 3 and a suspended housing 4; such casing and housing, when taken together, being hereinafter referred to as the shell. The casing 2 is, in effect, divided into an upper 45 and lower compartment 2^a and 2^b by means of a transverse partition 5. Such partition is here downwardly dished and is so shaped as to support a single capsule, preferably of almost as large a diameter as the diameter 50 of the casing; although it will be understood, of course, that the present invention may be carried out in connection with the use of a plurality of capsules at once. The partition or support 5 in the present case 55 has a single capsule seating shoulder as shown, surrounding the opening 6 at the

top of the support. The capsule is indicated at 7 and is provided with a bottom of gauze or metal filter cloth; this capsule being ground at its basal flange to make a tight joint with the support 5, so that all air passing between the interior of the casing 2 and the interior of the conical chamber established within the support 5, must pass through the interior of capsule 7.

The housing 4 is provided with a bottom cap 8 and threaded into openings in this cap are tubes 9 and 10, the interior of the horizontal tube 9 communicating with the interior of the cap itself, while tube 10 passes vertically through such cap and extends above the same through the center of housing 4, so that the upper end of tube 10 communicates, as shown, with the bottom of the conical chamber within support 5. The horizontal pipe 9 is here the air inlet and the vertical pipe 10 is here the air outlet. The air passing through the apparatus is indicated by the arrows. An exceedingly important feature of the present invention, 80 as will be explained more fully hereinafter, is the fact that a source of air under pressure, as for instance the force pump 9' shown, feeds the air inlet 9 of the new drier. A condenser and recipient (not shown) may 85 be connected in any suitable manner to the lower end of vertical pipe 10 when desired for condensing and collecting the distillate, as in the case of volatile oils which may be recovered and their amount determined.

The joint at the top of vertical tube 10 being, of course, a tight one, it will be seen that the ascending and descending streams of air, while they both have passages extending not only through casing 2 but 95 through housing 4, are entirely kept separate; the ascending air stream having an annular flow above the bottom cap 8 and until it becomes transformed into the descending flow when it reaches a point above 100 the upper edge of the capsule.

Such ascending air stream for a part of its course passes through an annular chamber located between a core 11 and a sleeve 12. The core 11 fixed on central vertical tube 105 10 is of a material having heat-resisting and dielectric qualities. The sleeve 12 is molded into place in housing 4 and is also of suitable heat-resisting and dielectric material. Arranged around core 11 is a spirally-wound 110 resistance element 13 connected by leads as indicated, and in a manner well understood

to be in circuit with a suitable source of electric current not shown, such circuit having interposed therein a switch 14 and a rheostat 15 for regulating the current and thus the temperature of resistance element 13, and, consequently, the temperature of the air passing through the annular chamber surrounding core 11 and also the temperature of the air circulating elsewhere 10 through the apparatus.

The parts just described, and particularly the parts 14 and 15 and the other electrical elements described, are, of course, preferable when electricity is available; but it 15 will be understood that where electricity is not available, other heating means may be used in connection with the drier for the air circulating therethrough or air exteriorly heated by any suitable means may be 20 forced through the drier in accordance with the present invention. In this connection, it will be appreciated that facilities for furnishing electricity to properly heat the resistance element 13 may not always be available 25 or the use of electricity may not be convenient or desirable.

The cover 3 is provided on its underside with a layer 16 of heat-resisting material, conveniently asbestos.

30 The cover is provided with a knob 17, preferably of heat-insulating material, and also with a thermometer 18 having its lower portion, which projects into the casing 2, housed in a protecting tube 19 of heat-conducting material.

35 The casing 2 is preferably covered by a heat-insulating shield, not shown, such shield being conveniently constructed of magnesium or a similar pipe covering 40 material.

In operation, a weighed quantity of the material to be tested is placed in capsule 7 and distributed over its foraminous bottom in a layer of suitable thickness and then 45 air under pressure is admitted through the horizontal tube 9 so as to set up a strong current of air to pass over resistance element 13, through the resistor of which electric current is flowing; this heated air under 50 pressure thereupon passing into the interior of casing 2, thence into the interior of the capsule, thence through the material to be tested and the foraminous bottom of the capsule, thence into the conical chamber 55 within the support 5 and below the capsule, and thence into the vertical outlet pipe 10 for discharge to the atmosphere or to a suitable condenser. The temperature of 60 the inflowing air under pressure is regulated by rheostat 15, such regulation being checked by observation of thermometer 18. After a sufficient exposure of the material in the capsule to the current of heated air under 65 pressure, running from about three minutes upwards, according to the nature of the

material subjected to the test, such material I have found is properly dried; whereupon, of course, the electric and air currents are discontinued and the loss of moisture during the drying is determined by the usual 70 laboratory methods. I have found that an apparatus as illustratively disclosed and as defined as to essentials in the appended 75 claims, permits such rapid desiccation that most materials will withstand higher 78 temperatures than in ordinary ovens.

It will be seen that my present invention provides a drier having certain structural features similar to those of the drier of my 80 said Patent No. 1,348,757, but it will be observed that my new drier differs therefrom essentially in that the current of air is forced over the heating element and thence through the material to be dried, while important 85 structural differences will be obvious in relation to supporting means for the capsule and the design of the parts, whereby improved guiding and confining passages for subdivisions of the air stream within the drier are provided, and whereby the parts 90 last-mentioned facilitate a drier construction of great economy in manufacture and assembly. As to the important feature of 95 a new drier involving the use of a stream of air which is not only heated but under positive pressure before it reaches the material to be tested, I have found that a continuous 100 flow of air through the entire apparatus set up by a positive pressure at the inlet, as here, rather than a flow of air through the drier established by an induced current or suction at the outlet, as in my said patent, results in a markedly improved operation. 105 As a possible explanation for such improved operation, I may say that I have found that 110 when the air circulation through the drier is caused by establishing a pressure different from atmospheric at the inlet of the drier, water evaporation in the material being tested occurs at a different rate and in a different manner than in driers as heretofore constructed. In this connection I have observed 115 that in a drier where the air flow through the same is established by setting up a pressure other than atmospheric at the outlet, the air stream at the zone within the drier where the material to be tested is located. The feature of the present invention now being discussed, is based on my new discovery 120 that an apparatus constructed as herein explained, may be used with great efficiency for very brief drying periods and particularly in the tobacco industry where incidentally it often occurs that a convenient means of obtaining sufficient suction is not available; 125 provided only that the drying period is made slightly longer than in an apparatus constructed according to my said patent. It will accordingly be seen that various modifications of the apparatus shown in the ac- 130

companying drawing may be made, and even a drier of the general structural type disclosed in the drawing of my said Patent No. 1,348,757, may be equipped with air pressure means at the inlet and operated as explained herein, within the scope of the present invention as defined by the appended claims.

I claim:

- 10 1. A drier, including a shell, a support therein for a capsule, a capsule on the support, said capsule having a foraminous bottom, an inlet and an outlet to the casing, a continuous air passage between said inlet and outlet and including two subdivisions having the side-wall of the capsule as a common wall separating the two subdivisions at their junction, the foraminous bottom of the capsule lying between said junction and the outlet, and means for increasing the temperature and pressure of air above the atmospheric and admitting such air to the passage subdivision between the inlet and the capsule side-wall.
- 20 2. A drier, including a shell, a support therein for a capsule, a capsule on the support, said capsule having a foraminous bottom, an inlet and an outlet to the casing, a continuous air passage between said inlet and outlet and including two subdivisions having the side-wall of the capsule as a com-

mon wall separating the two subdivisions at their junction, the foraminous bottom of the capsule lying between said junction and the outlet, means for admitting air under 35 pressure to the inlet, and means in the subdivision between the inlet and the capsule side-wall for heating said air under pressure.

3. A drier, including a shell, a support 40 therein for a capsule, a capsule on the support, an inlet and an outlet to the casing, an annular air passage interposed between the inlet and the capsule interior, and an air passage interposed between the bottom of the capsule and the outlet and surrounded 45 by said annular air passage.

4. The drier defined in claim 3, wherein 50 said support is downwardly dished below the capsule bottom to form an air chamber, said chamber communicating with the last-mentioned air passage at its top.

5. The drier defined in claim 3, wherein 55 said shell includes an upper casing, said capsule is the only one in the shell, a tubular member is provided below the support for the last-mentioned air passage, and the support is shaped to provide a chamber below the capsule bottom, said tubular member carrying said support and opening into said chamber.

GUILFORD L. SPENCER.
